UNITED STATES PATENT OFFICE.

FENTON FREDERICK STRATTON, OF EAST CROYDON, ENGLAND.

CARBURETOR FOR INTERNAL-COMBUSTION ENGINES.

Application filed November 3, 1924, Serial No. 747,636, and in Great Britain November 7, 1923.

The chief object of this invention is to provide a regulated and controlled means for delivering the liquid fuel in the carburetor preferably by gravity and without the use of float feed means for maintaining a constant level.

A further object of this invention is to simplify the construction of carburetors and to reduce the parts thereof in order that the cost of production may be reduced.

In the present invention I provide a small piston controlled nozzle arranged immediately adjacent and laterally with relation to a casing of the throttle valve which is preferably of the tapered plug type, and there may be two, three, or more such small piston controlled valves to operate as main nozzles in addition to the pilot nozzle.

I provide a screw down controlling needle adapted to control the passage of liquid fuel by means of a tapered point fitting loosely within a narrow orifice for the delivery of fuel. This orifice opens into the air passage of the valve.

The said tapered point is provided with adjustable means such as a suitable nut whereby the flow of liquid is accurately adjusted for a maximum and the liquid passes through a minute channel within a fixed sleeve into the pilot nozzle control chamber. I provide within the said control chamber which is preferably arranged horizontally with relation to the carburetor a small piston adapted to slide in said control chamber as a cylinder. The piston has fitted in the open end thereof a spring and the front or head of the piston is provided with a tapered point preferably steel which is adapted to fit or seat on the aperture in the other or inner end of the sleeve or nozzle provided with the said narrow or small orifice for the delivery of fuel. Thus the piston by means of the spring and the tapered point valve concentrically arranged on the head thereof, normally closes the fuel orifice.

A number of air holes are provided in the cylinder wall so arranged that they are very nearly closed when the spring loaded piston has its tapered valve point seated upon the fuel orifice.

Means are provided in each piston con-

sisting preferably of a cap or an adjustable sleeve for the other end of the spring to abut against, whereby the tension of the spring upon the said seated valve may be varied or adjusted without taking down the carburetor or removing the control valve thereof.

The said means may consist of a nut or nuts passing through a slot in the cylinder wall whereby the sleeve cap may be moved in the cylinder in order to increase or decrease the compression of the spring or a small lever with an eccentric may be provided on the exterior of the cylinder in order to vary the tension of the spring more readily.

The main nozzle piston or pistons if there are more than two main nozzles are of somewhat larger diameter than that provided for the pilot nozzle, but the operation in both cases is similar.

The throttle valve in this invention surrounds the main mixing chamber of the carburetor, and is adapted to be given a partial rotation within its casing, the casing having preferably cast therewith the nozzle cylinders.

In starting, when the suction of the engine is exerted upon the small pilot nozzle piston and valve, atmospheric pressure moves the piston against the action of the spring and opens the fuel orifice while air passing through the said air holes or passages sweeps the liquid fuel through the piston, through a port provided in the end of the cylinder and through a corresponding small passage in the throttle valve which registers with same. When the throttle valve is turned the said passage is closed, and the piston valve fits the seating, so preventing any further passage of liquid fuel by the pilot nozzle. Further movement of the throttle valve brings a port in the wall of same into register with the port in the main piston valve cylinder whereupon atmospheric pressure moves the piston valve against the action of the spring and opens the main nozzle to permit the passage of fuel. If a third piston valve and second main nozzle be fitted, this is opened by progressive further action of the throttle valve. On the opposite side

of the throttle valve a control cap with aperture is provided for additional air supply. When the throttle valve is moved to the full register of the port in same with the main nozzle port the piston valve has opened the main nozzle to the maximum.

Means are provided such as a disc fitted under the additional air inlet cap to control the amount of air permitted to pass.

10 In the appended drawings:—

Fig. 1 is a sectional elevation through the carburetor in the plane of the pilot nozzle.

Fig. 2 is an end view of the carburetor.

15 Fig. 3 is a sectional elevation from the plane of the main nozzle.

Fig. 4 is a plan section through the pilot and the main nozzle.

A is the main carburetor casing which has the plug throttle valve B fitted therein, the 20 passage or channel B' is formed laterally in the throttle valve B, and this passage is adapted to register for starting or slow running with the channel A' which is open to the cylinder A². In the cylinder A² is fitted 25 the piston C which is an easy sliding fit therein. The plate or diaphragm of the piston C has three or more ports D therein for the passage of air and the centre of the piston C has screwed therein the hardened 30 steel point E which point is adapted to fit and make a seating in the liquid fuel orifice in the nozzle or sleeve F, which is screwed into the cap or cover G of the cylinder in which is provided the channel G' for the 35 passage of the liquid fuel. The flow from the passage G' to the channel F³ is controlled by means of the adjustable screw H having a locking nut which screw is provided at the end with a tapered point H' 40 fitting within the channel F³ in the sleeve or nozzle. The channel F³ is contracted at F' and opens into the channel F² at the mouth of which the valve point E seats. When the carburetor is not in operation the tapered 45 valve point is kept upon its seating by the spring K². I is a port or passage communicating with the outer air, admitting air to the cylinder A² so that when the port A' 50 communicates with the passage B' and there is a negative pressure inside the carburetor, atmospheric pressure moves the piston C against the pressure of the spring to lift the steel pointed valve E from its seating in the nozzle F, permitting liquid fuel to pass 55 through into the cylinder. The movement of the piston C further opens the port or ports I so that the valve E is opened more widely and a greater amount of liquid fuel and larger volume of air are allowed to enter for starting. This air sweeps the liquid fuel deposited in the piston C through the 60 ports D by the port A' and the passage B' into the carburetor for the engine supply, the air being limited by the area of ports D.

65 By further movement of the throttle valve

by the lever N and the spindle O for acceleration, the passage B' is brought out of register with the passage A' and is closed, while the channel S leading to the main valve nozzle is partly opened by the port 70 B² in the throttle valve B, see Figs. 3 and 4.

The main valve nozzle also lettered F being of the same construction and operation is contained in the second cylinder A³ which is integrally formed with the cylinder A² 75 and the main carburetor casing A.

The several parts of the main nozzle having a similar construction and operation to the respective parts of the pilot nozzle and controlling valve, have the same lettering, 80 the air ports of the main nozzle however being of a larger size.

The passage H² to the main nozzle is immediately beneath the supply pipe L from the tank which is connected by the union L' to the cover G. A similar controlling tapered needle point H' with an adjusting nut for the screw H is fitted in the passage F³ of the main nozzle in which there is a similar valve E' of a much larger diameter, seating within the mouth or orifice of the nozzle. The port I' in the cylinder is of a much larger area for the admission of air, and the ports D' in the piston C' are also much larger to correspond, to permit the necessary volume of air to pass to supply air for combustion for the main nozzle.

The adjustable sleeve cap K and the spring K² are fitted in the cylinder A³ in an adjustable manner by nuts K'. By loosening the nuts the cap may be moved along the cylinder with regard to the nozzle to increase or decrease the tension of the spring and therefore the degree of opening of the nozzle. When therefore the port B² is 105 opened by means of the lever N, the piston C' slides forwardly in the cylinder A³ and progressively opens the air port I', at the same time progressively opening by means of the tapered valve E' the outlet for liquid fuel in the nozzle F until the full supply of like liquid fuel is permitted to pass through the nozzle F for the supply of the engine.

110 Additional air is fed to the carburetor through the channel R in the casing A which is arranged to register with the port B³, simultaneously with the registering of the port B² in the throttle valve with the port or channel S leading from the main nozzle.

115 When the requisite supply of air has been determined for a certain fuel, a disc having a suitable hole or aperture is fitted within the cap M screwed on to the exterior of the projecting tube of the channel R.

120 It will be observed that the port B³ will open progressively as well as simultaneously with the port B² during the turning of the 125 throttle valve.

The means for adjusting the position of the cap K by means of the nut K' are the same in the main nozzle as that described with reference to the pilot nozzle, for the purpose of varying as desired the tension of the spring without having to take the carburetor to pieces.

A second or a third main nozzle may be fitted when desired to a carburetor casing such as A, by extending the length of same, and similarly extending the length of the throttle valve B fitting within same.

Although the construction described and shown is specially applicable to the use of carburetors fed by gravity and having no float feed, the carburetor is adaptable and applicable if desired also to those having a float feed. This construction of carburetor has the particular advantage that it is applicable for use feeding at any desired angle with the engine and the inlet thereto.

The fuel feed cylinders may be horizontal as shown or vertical or at any desired angle thereto. A float feed in a carburetor necessitates the carburetor being arranged in practically one position only with relation to the level of the liquid in the float feed.

What I do claim as my invention and desire to secure by Letters Patent is:—

1. A carburetor comprising, a plurality of cylindrical mixing chambers, a liquid fuel inlet passage common to said plurality of mixing chambers, an adjustable fuel feed nozzle projecting into each of said mixing chambers, air ports in each of said mixing chambers, a suction-operated apertured piston valve slidably disposed in each of said mixing chambers, each of said piston valves controlling both the fuel feed nozzle and the air ports of its appropriate mixing chamber, a return spring bearing on each of said apertured piston valves, means operable externally of the carburetor to regulate the tension of each of said return springs, a throttle valve, means to oscillate said throttle valve, and ports in said throttle valve adapted to be caused to communicate in appropriate sequence with said mixing chambers.

2. A carburetor comprising, a plurality of cylindrical mixing chambers and a throttle valve casing, a throttle valve in said casing, means for oscillating said throttle valve, a liquid fuel inlet passage common to said plurality of mixing chambers, an adjustable fuel feed nozzle projecting axially into each of said mixing chambers, air ports in each of said mixing chambers adjacent to said fuel feed nozzles, a suction-operated apertured piston valve slidably disposed in each of said mixing chambers, a member carried by each of said piston valves to co-act with one of said fuel feed nozzles, each of said piston valves controlling both the fuel feed nozzle and the air ports of its appropriate

mixing chamber, the apertures in each of said piston valves serving to admit a mixture of fuel and air into the body of each of said mixing chambers, a mixture outlet port in each of said mixing chambers, ports in 70 said throttle valve each adapted to register in appropriate sequence with one of said mixture ports, a return spring bearing on each of said apertured piston valves, and means operable externally of said carburetor to regulate the tension of each of said return springs. 75

3. A carburetor comprising, a plurality of cylindrical mixing chambers and a throttle valve casing, a throttle valve in said casing, means to oscillate said throttle valve, one of said cylindrical mixing chambers being of smaller capacity than the remainder, a liquid fuel inlet passage common to said plurality of mixing chambers, an adjustable fuel feed 80 nozzle projecting from said inlet passage axially into each of said mixing chambers, air ports in each of said mixing chambers adjacent to said fuel feed nozzles, a suction-operated apertured piston valve slidably disposed in each of said mixing chambers, a member borne axially by each of said piston-valves to co-act with its appropriate fuel feed nozzle, each of said piston valves controlling simultaneously the fuel feed nozzle 85 and the air ports of its respective mixing chamber, a mixture outlet port in each of said mixing chambers, ports in said throttle valve each adapted to register in appropriate sequence with one of said mixture ports, a return spring bearing on each of said apertured piston valves, and means operable externally of said carburetor to regulate the tension of each of said return springs. 90

4. A carburetor comprising, a pilot cylindrical mixing chamber, a main cylindrical mixing chamber, a liquid fuel inlet passage common to said pilot and said main cylindrical mixing chambers, an adjustable pilot fuel feed nozzle, an adjustable main fuel feed nozzle, air ports in said pilot mixing chamber, air ports in said main mixing chamber, a suction-operated pilot piston valve slidably disposed in said pilot mixing chamber, a suction-operated apertured 100 main piston valve slidably disposed in said main mixing chamber, the former of said piston valves controlling simultaneously the pilot fuel feed nozzle and its adjacent air ports and the latter of said piston valves controlling simultaneously the main fuel feed nozzle and its adjacent air ports, a mixture outlet port in each of said mixing chambers, a return spring bearing on each of said apertured piston valves, means operable externally of the carburetor to regulate the tension of each of said return springs, a 105

throttle valve, means to oscillate said throttle valve, and pilot and main ports in said throttle valve adapted to be caused through 110

- said mixture outlet ports to communicate in appropriate sequence with said pilot and main mixing chambers.
5. In a carburetor, a cylinder having in its side wall at one end an air inlet and at its other end in its end wall a port, a spring pressed piston valve in the cylinder and controlling the air inlet, said piston valve having adjacent one end an apertured partition, a conical valve projecting from the partition, a feed nozzle projecting into the cylinder, a throttle valve casing in which the cylinder is secured and an oscillating throttle valve in said casing and having a port adapted to register with the port of the said cylinder.
6. In a carburetor, a throttle valve casing, an oscillating throttle valve in the casing and having ports of different sizes, two cylinders secured to the said casings and each having a port in its end, the ports being of different sizes, a spring-pressed piston in each cylinder and controlling the air inlet thereof, each piston valve being provided with an apertured partition adjacent its end, a conical valve projecting from the partition of each piston valve, the valves being of unequal size, and a feed nozzle projecting into each cylinder and into which the conical valve of the piston valve projects.

FENTON FREDERICK STRATTON
